UNITED STATES PATENT OFFICE.

JOHN P. KIRCH, OF PITTSBURGH, PENNSYLVANIA.

DESIGN FOR A TIRE.

57,667.

Specification for Design.

Patented Apr. 26, 1921.

Application filed June 26, 1920. Serial No. 392,091. Term of patent 14 years.

To all whom it may concern:

Be it known that I, JOHN P. KIRCH, a citizen of the United States, residing at Pittsburgh, in the county of Allegheny and State of Pennsylvania, have invented a new, original, and ornamental Design for Tires, of which the following is a specification, reference being had to the accompanying drawing, forming part thereof.

Figure 1 is a plan view of a tire showing my new design, and Fig. 2 is a section on line 2—2 of Fig. 1.

I claim:

The ornamental design for a tire, as shown.

JOHN P. KIRCH.
